UNITED STATES PATENT OFFICE.

HERBERT WILSON, OF TOLEDO, OHIO, ASSIGNOR TO THE DURA COMPANY, OF TOLEDO, OHIO, A CORPORATION OF DELAWARE.

DESIGN FOR A PAWL STUD.

Application filed January 28, 1924. Serial No. 8,448. Term of patent 7 years.

To all whom it may concern:

Be it known that I, HERBERT WILSON, a citizen of the United States of America, residing at Toledo, in the county of Lucas and State of Ohio, have invented a new, original, and ornamental Design for a Pawl Stud, of which the following is a specification, reference being had therein to the ac-

companying drawings, forming part thereof, in which Fig. 1 is a plan view of a pawl stud, showing my new design; and Fig. 2 is a side view thereof.

I claim:

The ornamental design for a pawl stud, substantially as shown.

HERBERT WILSON.
